UNITED STATES PATENT OFFICE.

WOLF HEILBRUNN, SIMON BLÜTH, AND WILHELM PAPE, OF BERLIN, GERMANY.

MUSIC-RECORDER.

No. 884,580.

Specification of Letters Patent.

Patented April 14, 1908.

Application filed May 19, 1905. Serial No. 261,214.

To all whom it may concern:

Be it known that we, WOLF HEILBRUNN, SIMON BLÜTH, and WILHELM PAPE, citizens of Germany, residing at 39 Keibelstrasse, 5 Berlin, Germany, have invented new and useful Improvements in Music-Recorders, of which the following is a specification.

Our invention relates to apparatus for pneumatically marking note or record sheets 10 for automatic musical instruments while the piece is being played by hand, so that the sheet will enable exact reproduction of the piece of music.

The essential feature of the invention is 15 that the recording point for each note is actuated directly by a bellows, the interior of which, on depression of the corresponding key of the instrument, is brought into connection with a low pressure chamber, owing 20 to the opening of an air passage and actuation of a change valve. In this manner extremely accurate and simple transmission is attained. A still more rapid succession of operations for trilling or shaking or the like 25 can be insured by the provision of an extra low pressure chamber communicating with the said passages between the key-actuated valve and the change valve.

Our invention is illustrated in the accompanying drawing, in which

Figure 1 is a front elevation of a portion of a piano to which the new recorder is attached. Fig. 2 is a section on the line A—B of Fig. 1.

30 *a* is a portion of a piano on which is mounted an attachment of well-known description for winding up and off the record sheet *d*, consisting of the rollers *b* and *c*, on which the record sheet is wound. This sheet is wholly 35 blank, being provided neither with graphic marks nor perforations. The rollers *b* *c* may be driven in any suitable manner (preferably 40 electrically) the driving mechanism being adjusted corresponding to the time of the piece 45 of music to be recorded.

On the sheet *d* the notes are mechanically recorded in the following manner. On the keys *e* being struck, the rear lever-arm *f* actuates valves *g*, whereby the mouth of a 50 passage *h* is opened. By the entrance of air into this passage a diaphragm *i* will be moved, whereby in well-known manner a

change-valve *k* is operated. On this valve *k* moving to the left, it closes the aperture *l* which conducts to the outside, and the interior of the bellows *m* is connected with the low pressure chamber *n*. The bellows *m* immediately collapses and the rod *q* and bell lever *o* press the pencil or other marking point *p* against the surface of the unwinding 55 sheet *d*. As long as the key *e* is depressed and air has access to the passage *h*, the point *p* remains pressed against the unwinding sheet *d* and thus makes a mark in order that the part can subsequently cut out of the sheet. 60 For each key the arrangement is naturally exactly the same and likewise for the pedals. When the sheet has thus been fully marked, it can be stamped out in well-known manner, the perforations made being of exactly 65 the length of the marks made by the point *p*. The low pressure in the chambers *n* is produced by a bellows or the like, from which a flexible pipe *r* conducts to the said chambers.

In order to again suck the atmospheric air 70 out of the various passages *h* again, another chamber *s* is provided, connected with the suction bellows by a flexible pipe *t*.

Having thus described our invention, what we claim as new and desire to secure by Letters 80 Patent of the United States is:—

A music recorder comprising in combination for each key, a low pressure chamber having an atmospheric air inlet at one side, a valve for closing said inlet, a diaphragm in 85 the said chamber, a bellows communicating with the chamber at the other side of the diaphragm, a valve controlling the communication of the chamber with the bellows and actuated by the diaphragm, a point adapted 90 to mark the traveling record sheet, a bell crank lever connected to said point and a single rod connected at one end to the bellows and at the other to the bell crank lever, substantially as described.

In testimony whereof we have signed our names to this specification in the presence of two subscribing witnesses.

WOLF HEILBRUNN.
SIMON BLÜTH.
WILHELM PAPE.
